UNITED STATES PATENT OFFICE.

ALVA F. WARREN, OF PROVIDENCE, RHODE ISLAND.

GUN-MOUNT.

SPECIFICATION forming part of Letters Patent No. 638,857, dated December 12, 1899.

Application filed June 5, 1899. Serial No. 719,445. (No model.)

To all whom it may concern:

Be it known that I, ALVA F. WARREN, a citizen of the United States, residing at Providence, in the State of Rhode Island, have invented a new and useful Improvement in Gun-Mounts, of which the following is a specification.

My invention relates to new and important improvements in the construction of gun-mounts.

The several objects of my invention are, first, to provide a gun-mount that can be kept turning around in a circle all of the time while the gun is being fired or stand in one position while said gun is being fired; second, to provide facilities for shielding those who work the said gun-mount; third, to provide means for preventing a greater part of the recoil of the gun; fourth, to provide improved means for lubricating the bearing-rollers in the foundation base-plate of the gun-mount, and, fifth, to provide means for clamping the said gun-mount in any desired angular position.

In the accompanying drawings, Figure 1 represents a side elevation of the gun-mount. Fig. 2 represents a detail rear view showing the foundation-bed and the rotary base-block of the gun-mount. Fig. 3 represents an axial section of the gun-mount, showing the bearing-rollers upon which the gun-mount is made to rotate. Fig. 4 represents a detail section showing the slide of the protective shield. Fig. 5 represents a detail view of the protective shield, showing the slide and a cross-section of the barrel of the gun.

In the drawings, 1 represents the barrel of the gun.

2 represents the rotative base-block, to which the gun is pivotally attached by means of the trunnions 33 33, projecting outward on each side of the arm 34, which extends downward from the under side of the barrel of the gun.

The rotary base-block 2 is pivoted to the circular foundation-bed 3 by means of the stud 88, provided at its lower end with the nut 89, and the foundation-bed is provided with the circularly-arranged series of recesses 100 100, adapted for the reception of the antifriction-rollers 90 90, upon which the base-block 2 is caused to rotate, the said base-block being clamped in any desired position of its rotative

movements by means of the tightening-screw 92 and its hand-wheel 91. I also provide a channel or space in connection with the recesses 100 to convey oil from the said recesses to the pivot-stud 88, and a single oil-hole 93 is made in the base-block 3 for supplying oil to the rollers 90, which rotate in the recesses 100, the oil being retained in the said recesses, so that the moving parts will be thoroughly lubricated at all times.

The foundation-bed 3 is provided with the upwardly-projecting circular gear 36, with which the gear 30, revolving upon the stud 101, is made to engage, the said stud being attached to the base-block 2, so that when the gear 30 is caused to revolve upon the stud 101 the said base-block 2 will be caused to turn upon the bearing-rollers 90, and in order to impart the desired rotary movement to the gear 30 I provide a driving-gear 29, secured to the inner end of a shaft which has its bearings in the end of the hand-actuated lever 31. The gear 29 may be thrown into and out of engagement with the gear 30 as desired, and for the purpose of securing the gear 29 out of its engagement with the gear 30, as shown in Figs. 1 and 2, I provide a removable pin 39, which enters a suitable hole in the base-block 2, the said pin being provided with an attaching-chain 38, secured to the base-block by means of the eye 37.

The foundation-bed 3 is provided with a circular track 47 for supporting the semicircular protective shield 42, which is secured to the base-block 2 by means of the braces 26 and 27, attached to the ears 28 at opposite sides of the base-block, and the braces 23 and 24, secured to the opposite sides of the base-block by means of the screws 102 102.

The protective shield 42 is provided with a strengthening-rim 45, bolted to the inner side of the lower edge of the shield, and upon a stud 103 are placed the loose rollers 46, which serve to support the weight of the shield as it moves around the circular track 47, which is so arranged that the shield is below the outside face of track, thereby preventing any ball from getting under the said shield, as shown in Fig. 1.

When the base-block 2 is being turned upon the rollers 90 of the foundation-bed 3, the protective shield 42 is provided at its face with

a slot 104 (shown in dotted lines in Fig. 5) and also with the parallel ways 43 43, riveted to the outer surface of the shield, and between the said ways and over the said slot is placed 5 the loose slide 44, provided with a perforation adapted to receive the barrel of the gun and with the sight-opening 48 above the barrel. (Shown in Fig. 5.) The weight of the slide 44 is supported by means of the wire cords 10 96, which are connected to the slide and pass over the pulleys 106 107 and are provided at their outer ends with the counterbalancing-weights 95 95, and by this means the barrel 15 of the gun will be freed from all the weight of the slide 44, and, if desired, the slide may be clamped to the shield by means of the hand-wheel and screw 97, the said screw passing through the fixed nut 98.

The gun is provided at its under side with 20 the circular segment 25, which passes through an opening 105 made in the base-block, and the gun may be clamped in any vertical plane by means of the said circular segment and the clamping-screw and hand-wheel 20, the said 25 segment 25 being connected to the gun by means of the pins 69.

The side braces 21 and 22, which are connected to the side of the gun by means of suitable pivot-studs 108, are arranged to pass 30 through openings 109 made in the loosely-pivoted studs 40 and 41, which are secured to the ears 110 of the base-block, and these side braces when clamped by means of the screws 19 19 will serve to check the recoil of the gun 35 when fired.

I claim as my invention—

1. In a gun-mount the combination of the foundation-base provided with the circular gear; the base-block pivoted to the foundation-base for rotary movement; and the loose

gear-pinion connected to the base-block and engaging with the circular gear of the foundation-base; with the hand-operated gear held upon a lever pivoted to the base-block and adapted for engagement and disengagement 45 with the gear-pinion whereby the gun may rotate continuously in either direction, by means of the gears, or be disengaged from the gears and moved by hand, substantially as described. 50

2. In a gun-mount the combination of the foundation-base provided with the circular track and the rotary base-block pivoted thereto, with the semicircular shield having its lower edge fitting the circular track, and the 55 braces secured to the forward portion of the shield and the opposite sides of the base-block; also the slide in shield with counterbalancing-weights and hand-wheel for clamping slide to shield, substantially as described. 60

3. In a gun-mount the combination of the foundation-base, provided with the circular track, and the rotary base-block pivoted thereto, the gun pivoted to the rotary base-block by means of trunnions arranged upon an arm 65 which extends below the barrel, the circular segment secured to the under side of the gun-barrel, and passing through the base-block, the clamping-screw for holding the gun-barrel in a set position, the semicircular shield 70 having its lower edge fitting the circular track, the slide in the shield fitting over the barrel of the gun, the balancing-weights, and the hand-wheel for clamping the slide to the shield, substantially as described.

ALVA F. WARREN.
